LIGHTING DEVICE

Herbert E. Toelle, Milwaukee, Wis., assignor to
 Milwaukee Gas Specialty Co., Milwaukee, Wis.,
 a corporation of Wisconsin

Application May 5, 1930. Serial No. 449,820

4 Claims. (Cl. 158—115)

My invention relates to lighting devices, particularly of the type employed in connection with gas ranges for lighting the burners thereof, and contemplates an improved construction, wherein, 5 the hood of the torch head is formed as a unit with or integral part of the grate of the gas range.

More particularly my invention relates to the type of torch head adapted for use with gases having relatively high heating or B. t. u. values 10 in which the torch head is provided with a flame projecting arrangement for preventing the lighting flame or flames from curving or rising upwardly away from and missing the burners.

My invention is illustrated in the accompanying drawing, in which:

Figure 1 is a fragmentary perspective view of a gas range showing an embodiment of the present invention therein;

Figure 2 is a bottom plan view of the grate 20 structure and torch head arrangement;

Figure 3 is a vertical detail section taken on the line 3—3 of Figure 2;

Figure 4 is a fragmentary vertical detail section taken on the line 4—4 of Figure 2;

Figure 5 is a fragmentary perspective view showing another form of lighter hood with the grate broken away and partially in section; and

Figure 6 is a side elevational view of another 30 form of hood again with the grate broken away and partially in section.

The gas range is illustrated at 5. It is provided with a grate 6 overlying the burners 7 and 35 removably supported marginally at 8 upon a marginal ledge or other supporting means along the inner margin of the frame 9 in the manner of existing grate arrangements, of which the particular grate shown is illustrative.

The usual existing stringer pipe 10 supplies fuel to the burners 7, and the burner fuel supply connections are individually controlled by burner control valves 11 in the usual or any suitable manner.

The grate 6 shown is of sectionalized and specifically two-part construction divided at 12 and 45 comprising a pair of grate sections 13, each provided with a generally rectangular frame 14, in each of which frame 14 is a front and a rear arrangement of grate bars 15 and 16 formed as an integral or unitary part of the frames 14 and 50 adapted for supporting the cooking vessels over the respective burners. The particular arrangement of the grate bars shown is illustrative and may vary widely.

The lighter tube 17 is connected to the stringer pipe or gas manifold 10, and adjacent the con-

nection is a valve 18 of the type in which a restricted-by-pass for the gas maintains a small pilot flame at the lighter tip 19 of the torch head, and in which depression of the external button 20, manually, effects the flow of a considerably increased amount of gas in order to project the flame to the burner which it is intended to light. The lighter tip 19 is mounted upon the upturned outer end 21 of the lighter tube 17, and when the parts are brought into operative relation, as 65 shown in Figure 1, takes position within the hood 22.

The hood 22 is formed as an integral unitary part of the grate 6, being divided in the particular grate arrangement shown along the line of division 12 between the grate sections 13 with one-half 22a of the hood formed as an integral unitary part of one grate section 13, and the other half 22b of the hood formed as an integral unitary part of the other grate section 13. When 70 the grate sections 13 are mounted in the frame 9, the bringing of the sections of the grate into operative relation for use also brings the two hood parts together, and in such relation as to complete the hood, forming, in effect, a substantially unitary enclosure for the lighter tip 19. The hood 22 is open at the bottom and may have an opening 23 at the top formed by complementary opening portions in the upper wall portion 75 24 of the hood parts.

Each of the hood parts 22a and 22b has openings 25 through which the lighting flames are projected to the burners 7, and a pair of flame projecting arrangements, one for each of the two burners on the corresponding side of the range, these flame projecting arrangements comprising, in this particular embodiment, inverted channels 26 formed at their torch head ends as an integral unitary part of the corresponding hood parts 22a, 22b. The inverted channels extend outwardly from the hood over the top of the lighting flames and form obstructions for preventing the outer ends of the lighting flames from curving or rising upwardly and missing the burner when a gas of high calorific or B. t. u. value is employed, and by a gas of high calorific or B. t. u. value, I mean a gas with a calorific or B. t. u. value higher than heretofore successfully employed with lighters of this sort, and more specifically, a gas such as described in the co-pending application of Oscar J. Leins, Case 11, Serial No. 449,854, filed May 5, 1930.

In Figure 5 the hood instead of being divided wholly along the line of division 12' between the grate sections 13', has a portion along the top 100 105 110

of each side overhanging the adjacent portion of the other side at 28. This forms on the hood 22' a vertical interlock for the grate sections 13', it being understood that where this vertical interlock is not formed on the hood the interlock may be formed on the grate sections independently of the hood, as is now commonly done where the hood is separate from the grate, or where there is no lighter at all.

10 In Figure 6 the flame projecting arrangement instead of comprising inverted channels formed as an integral unitary part of the hood, comprises tubes 30, which may be formed of sheet metal, or the like, and which are mounted in openings 31 in the walls of the hood sections 32a, 32b. The tubes 30 are shown as being slit longitudinally along the bottom, but it is to be understood that the openings at the bottoms of the tubes may be of other form than the longitudinal slits 34, as shown. The inner ends of the tubes 30 may be additionally supported within the hood in the general manner disclosed in the copending Leins application above referred to. The sides of the hood parts 32a, 32b may be provided with openings 35 which may be in addition to, or in lieu of the opening 23 of the embodiment shown in Figures 1 to 4, or the top opening of that embodiment may be employed alone in this embodiment, as desired.

30 I claim:

1. In combination, a plurality of gas burners, a lighter adapted for maintaining a pilot flame in proximity to the burners and provided with ports directed toward the respective burners, a pair of grate sections covering the burners, a hood covering the lighter tip and comprising a pair of complementary and generally semi-cylindrical parts, one formed as an integral unitary part of and depending from each of said grate sections at the abutting edges thereof, said hood parts being brought together by assembly of the grate sections to form a generally cylindrical depending hood, the grate section along the top of the hood having complementary openings forming an outlet at the top of the hood, a plurality of channels, one for each of the burners, said channels each formed as an integral unitary part of the hood parts and extending outwardly from the hood, means independent of said channels for projecting the pilot flame outwardly from the hood and through the channels in directions toward the respective burners, said channels being open along the bottom to provide for obstructing the rise of the flame without extinguishing the flame and

each of said channels extending from said hood a distance sufficient to increase the distance each flame is projected toward its burner.

2. In combination, a plurality of gas burners, a lighter for maintaining a pilot flame centrally of and substantially coplanar with said burners, a pair of grate sections supported above and extending over the burners, a hood covering the pilot flame and comprising a pair of complementary and substantially semicylindrical parts disposed at the abutting edges of said grate sections, said hood parts having portions providing for interlocking engagement against vertical movement when assembled, the grate sections having complementary openings forming an outlet at the top of said hood, channels projecting from said hood toward each of said burners, and means for projecting the pilot flame through said channels to ignite said burners.

3. In combination, a plurality of gas burners, a lighter for maintaining a pilot flame centrally of said burners, a pair of grate sections supported above and extending over the burners, a hood covering the pilot flame and comprising a pair of complementary and substantially semicylindrical parts disposed at the abutting edges of said grate sections, said hood parts having portions providing for interlocking engagement against vertical movement when assembled, the grate sections having complementary openings forming an outlet at the top of said hood, integral individual channels extending from said hood along said grate sections, said channels being supported only at said hood, and means for projecting the pilot flame through said channels to ignite said burners.

4. A grate adapted to extend over and be supported above a plurality of gas burners, comprising a pair of grate sections, said sections having abutting engagement along complementary edges thereof, a hood formed integral with said grate comprising a pair of complementary and substantially semicylindrical parts disposed at the abutting edges of said sections and forming a generally cylindrical depending hood when said sections are in abutting position, said hood parts having overhanging portions providing for interlocking engagement of said grate sections, said grate sections having complementary openings forming an outlet at the top of said hood, and channels formed integral with said hood and extending laterally therefrom below said grate sections.
